WINDSHIELD WIPER UNIT

Fred A. Krohm, Hobart, Ind., assignor to The Anderson Company, a corporation of Indiana

Application July 6, 1954, Serial No. 31,287

Term of patent 14 years

(Cl. D14—6)

Figure 1 is a top view of the windshield wiper unit showing my new design;

Figure 2 is a side view in elevation of the unit illustrated in Figure 1; and

Figure 3 is an enlarged end view in elevation of the unit illustrated in Figure 2.

The essential features of my design reside in the portions shown in full lines.

I claim:

The ornamental design for a windshield wiper unit, as shown and described.
